UNITED STATES PATENT OFFICE.

CHARLES E. RENSHAW AND ELLIS C. HEALY, OF EAST ORANGE, NEW JERSEY,
ASSIGNORS TO NEWMAN CLOCK COMPANY, INC., OF NEW YORK, N. Y., A COR-
PORATION OF NEW YORK.

SUPERVISORY MECHANISM.

1,407,812.

Specification of Letters Patent. Patented Feb. 28, 1922.

Application filed July 20, 1918. Serial No. 245,652.

To all whom it may concern:

Be it known that we, CHARLES E. RENSHAW and ELLIS C. HEALY, both citizens of the United States, residing at East 5 Orange, in the county of Essex and State of New Jersey, have invented certain new and useful Improvements in Supervisory Mechanism, of which the following is a full, clear, and exact description.

10 The invention which constitutes the subject-matter of this application relates to supervisory mechanism and has to do with a device for controlling access to a key contained in a receptacle located adjacent to 15 a valve which constitutes a part of a sprinkler or other system. One of the important features of the invention consists in the provision of inexpensive and simplified mechanism for controlling access to the key 20 or other instrument for producing a record upon the record dial of a watchman's clock; that is to say, when the valve is open, as it normally should be, access may be had to the watchman's key; but, if the valve is closed, 25 or partly so, the key or other instrument for producing a record upon the record dial of a watchman's clock is not available. Each valve of the system is equipped with 30 a receptacle so as to enable the watchman, when the valve is in normal position, to effect a record upon the record dial of his clock which will indicate the time at which the station was visited. So long as these 35 records are made at the required intervals, it is a sure indication that the valve at those particular times was open. But, if a record is not effected, as will be apparent from the examination of the record dial, it is an indication that the valve at that 40 particular time was not in normal position. If, however, it is a part of the watchman's duty to open the valve, or, more accurately speaking, to move it back to normal position, he can then, of course, make the necessary 45 record on the record dial. In any event, the invention will have served its purpose.

Another feature of our invention consists in providing a device of the kind described whereby the key receptacle may be readily 50 located at variable distances from the valve to which it is connected.

In the drawings:

Figure 1 illustrates a side view of the

preferred embodiment of our invention, certain parts of the valve and certain parts of 55 the key receptacle being illustrated in section to show the interior construction.

Figure 2 is an enlarged view of the key receptacle taken at right angles to the view illustrated in Fig. 1, the lower part thereof 60 being broken away to illustrate further details of construction. Figure 3 is a detail.

Referring to the drawing in detail, the reference numeral 10 designates the water supply to the sprinkler coming from any 65 suitable pipe (not shown). Located in this supply is a valve 11 provided with a yoke 12, a threaded sleeve 13 rotatably mounted in the yoke, a valve-stem 14 screw-threaded to the sleeve, and a manipulating hand-wheel 15 fixed to the sleeve 13 and adapted to rotate the same in order to impart the longitudinal movement to the valve-stem 14 and the gate valve (not shown) attached thereto. The mechanism just described is 75 old and well known and we make no claim thereto except as it constitutes or is an element of the combination.

The valve-stem 14 projects substantially 80 above the manipulating-wheel 15 and surrounding this upwardly-projecting portion is a sleeve 16 screw-threaded or otherwise rigidly secured to a base 17 which is in turn fixed, as by bolts 18, to the hand-wheel 15. This sleeve 16 is swiveled, by means of the 85 members 19 and 20, to one end of a rigid tubular member 21, the other end of said member being connected by any suitable means to the receptacle-container 22.

The receptacle-container 22 may, of 90 course, be of any configuration, but its longitudinal length is sufficient to enable a substantial reciprocation of the key-receptacle 23 which is contained therein. Within the tubular member 21 is contained a flexible 95 liner, 24, the length of which, as will be apparent from the drawing, is substantially the same as the length of the tubular member 21. Within the liner 24 is a flexible and tubular wire coil 25 which fits the liner 100 rather snugly and within this coil is a flexible rod 26. The corresponding terminals of the shaft 25 and rod 26 are secured to each other, and in turn to the valve stem 14 and key receptacle 23, respectively. The 105 object of the liner 24 is to avoid any back-

normally registering with the opening in the container, and means actuated by the movement of the valve from its normal position to impart a reciprocating movement to said receptacle to bring said openings out of registry.

6. In combination, a valve, a manually operable indication-producing means, means for rendering said first named means operable or inoperable, and means comprising a helical, longitudinally-movable member connecting said valve and second named means.

7. In combination, a valve, a manually operable indication-producing means, means for rendering said first named means operable or inoperable, means comprising a lon-

gitudinally-movable flexible member connecting said valve and second named means, and a spiral winding surrounding and movable with said member.

20

8. A supervisory mechanism as specified in claim 1 in which the flexible means is surrounded by a tubular member for impeding access to said means.

9. A supervisory mechanism as specified in claim 2 in which the flexible means is surrounded by a tubular member for impeding access to said means.

In testimony whereof we hereunto affix our signatures.

CHARLES E. RENSHAW.
ELLIS C. HEALY.
